REGULATING DEVICE USING COPPER
OXIDE RECTIFIERS

Bernard E. O'Hagan, Swissvale, Pa., assignor to
The Union Switch & Signal Company, Swiss-
vale, Pa., a corporation of Pennsylvania

Original application October 14, 1930, Serial No.
488,574, now Patent No. 1,966,558, dated July
17, 1934. Divided and this application March
31, 1933, Serial No. 663,757

3 Claims. (Cl. 175—294)

My invention relates to regulating devices using copper oxide rectifiers.

I will describe one form of apparatus embodying my invention, and will then point out the novel features thereof in claims.

In the accompanying drawing, Fig. 1 is a curve showing certain electrical characteristics of a copper oxide rectifier. Fig. 2 is a diagrammatic view showing one form of apparatus embodying my invention.

The present application is a division of my copending application Serial No. 488,574, filed October 14, 1930, Patent No. 1,966,558, granted July 17, 1934, for Regulating devices using copper oxide rectifiers.

Referring first to Fig. 1, the curve shown in this view illustrates the voltage-resistance characteristic of the copper oxide rectifier described and claimed in United States Letters Patent No. 1,640,335, granted to L. O. Grondahl on August 23, 1927. This curve shows that as the voltage across the rectifier increases, the resistance in the low resistance direction decreases, and that the decrease of resistance is much more rapid at low voltages than at high voltages.

Referring to Fig. 2, the reference character A designates a railway switch which is actuated by an electric motor M having an armature 1 and a field 2. Operatively connected with the switch is a cut-out controller D comprising a contact arm 59 and contacts 3 and 4. Contact 3—59 remains closed at all times except when the switch is in the reverse position and contact 4—59 remains closed at all times except when the switch is in the normal position.

The motor M is controlled in part by a circuit controller P which is in turn controlled by a pole-changer L which may be incorporated in a switch lever of an interlocking machine. The circuit controller P comprises an electromagnet 9, made up of two windings 9^a and 9^b, and a polarized winding 10 which is preferably provided with a steel permanently magnetized core 11. Pivotaly attached to the core 11 is an armature 12 which is therefore polarized by flux from the permanent magnet core 11 at such times as winding 10 is not carrying current. It follows that when the electromagnet 9 is supplied with current of one polarity the armature 12 will be swung in a clockwise direction, but that when current of the opposite polarity is supplied to electromagnet 9 the armature will be swung in the opposite direction. The armature 12 controls three movable contact yokes 13, 14 and 15 through suitable linkage, in such

manner that the yokes occupy their right-hand positions when the armature is swung to the left, and vice versa.

The reference character N designates a neutral magnet which controls a pivoted armature 17, the lower end of which projects into the path of movement of a portion of armature 12 to prevent the reversal of the armature when the neutral magnet N is deenergized. Pivotally attached to the armature 17 is a link 19 provided with a slot 42 which at times engages a pin 43 in a rocker arm 70 which carries a contact finger 20. When magnet N is deenergized, the link 19 moves the rocker arm 70 against the bias exerted by spring 44 into a position in which the contact 20 connects wire 33 with wire 34. When neutral magnet N is energized, however, the spring 44 urges the rocker arm 70 into a position wherein the contact between wires 33 and 34 is interrupted. As shown in the drawing, the switch A occupies its normal position; the neutral magnet N is deenergized thereby locking armature 12 of circuit controller P in its left-hand position.

The apparatus thus far referred to in Fig. 2 is illustrated and described in United States Letters Patent No. 1,722,364, granted to Henry S. Young on the 30th day of July, 1929, for Railway traffic controlling apparatus.

The reference character R designates an automatic circuit breaker. Circuit breaker R comprises a primary core 25 on which are windings 23 and H, and a secondary core 24 on which is a winding H¹. Associated with core 25 is an armature 21 which is normally held open by rod 27 due to the action of compressed spring 22 and at times due to the attraction of armature 26 to the face of core 24. Rigidly attached to rod 27 is a detent 57 which raises link 19 when armature 21 is attracted. When link 19 is raised, pin 43 is disengaged from slot 42 and rocker arm 70 moves to the right, due to the bias exerted by spring 44, moving contact finger 20 to the right and thus breaking contact between wires 33 and 34. In series with coil 23 is a rectifier 40, and both coil 23 and rectifier 40 are connected across field 2 of motor M. Coil 23 and rectifier 40 are connected across field 2 through wire 32, rectifier 40, wire 32¹, winding 23, and wire 35. Coil 23 is energized by the voltage drop across field 2.

In order to prevent tripping circuit breaker R, when power is first applied to motor M and the drop across field 2 is high, the circuit breaker is so designed that when the flux

builds up in core 25, a voltage will be induced in coil H which voltage will send current through the winding H¹ on core 24, magnetizing core 24 and attracting armature 26. Armature 21 will therefore remain open and the circuit breaker will not trip. When motor M speeds up, the voltage drop across armature 1 increases and the voltage drop across field 2 decreases. If the switch becomes obstructed while moving 10 to the normal or reverse position so that the motor runs at a low speed, due to the slipping of the motor clutch, the voltage drop across field 2 will increase and when the voltage drop has increased beyond a certain value, the resistance 15 of rectifier 40 will decrease to a point where sufficient current will flow through coil 23 to attract armature 21 and trip the circuit breaker.

Motor M has a normal and a reverse operating circuit, and its direction of rotation depends on 20 the position of contact 59 of circuit controller D and yokes 13, 14 and 15. When the switch is to be moved to the reverse position, the motor operating circuit is from terminal B, through wire 5¹, wire 33, contact finger 20, wire 34, wire 25 28, yoke 13, wire 16, armature 1, wire 18, yoke 14, wire 31, contact 3, contact 59 and field 2 to terminal C. When the switch is to be moved to the normal position, the motor operating circuit is from terminal B, through wire 5¹, wire 33, 30 contact finger 20, wire 34, wire 29, yoke 14, wire 18, armature 1, wire 16, yoke 13, wire 30, contact 4, contact 59 and field 2 to terminal C.

In describing the operation of the apparatus, I will assume it is desired to move switch A to the reverse position. Pole-changer L is first reversed and current flows from terminal B, through wire 7, yoke 15, neutral magnet N, and wire 6¹ to terminal C. Neutral magnet N is energized and armature 17 is attracted, closing 35 suitable contacts to energize polar relay P in the reverse direction. Armature 12 then moves to the right, moving yokes 13, 14 and 15 to the left, closing contacts which complete the motor circuit when armature 17 is released connecting wires 33 and 34 through contact finger 20. The switch now moves to the reverse position. If an 40 obstruction occurs in switch A, the motor runs at a low speed and the voltage across field 2 increases beyond a value necessary to decrease 45 the resistance of rectifier 40 for sufficient current to flow through winding 23 to attract armature 21. Detent 57 will then raise link 19 and slot 42 will disengage from pin 43. Rocker arm 70 will move to the right due to the bias exerted 50 by spring 44 and the contact between wires 33 and 34 will open, opening the motor circuit. The circuit breaker once having been tripped 55 will not reset until the controller P has moved to the opposite position. Resetting controller P is accomplished by moving pole-changer L to the position shown on the drawing. Current will now flow from terminal B, through bus 5, wire 8, yoke 15, neutral magnet N, and wire 6¹ to terminal C. Magnet N is energized and attracts armature 17 which moves link 19 so that 60 slot 42 engages pin 43. Suitable contacts are closed when armature 17 is attracted to energize polar relay P in the normal direction. Armature 12 then moves to the left, moving yokes 13, 65 14 and 15 to the right and closing contacts which complete the motor circuit for reverse rotation when armature 17 is released connecting wires 33 and 34 through contact finger 20. When the switch returns to the original position, 70 the operation may be repeated as first described.

In a similar manner if the switch is to be moved from the reverse position to the normal position, the pole-changer L is moved to the position shown in Fig. 2. Magnet N is then energized and armature 17 is attracted, closing suitable contacts to energize polar relay P in the normal direction. Armature 12 then moves to the left, moving yokes 13, 14 and 15 to the right, closing contacts which complete the motor circuit when armature 17 is released connecting wires 33 and 34 through contact finger 20. The switch now moves to the normal position. If an obstruction occurs in switch A while it is moving to the normal position, the resistance of rectifier 40 will be decreased due to increased voltage across field 2, causing breaker R to trip, as previously described, thus protecting motor M. To return the switch to the reverse position, pole-changer L will again be reversed, energizing magnet N and reversing controller P, in the manner previously described. After the switch returns to the reverse position, another attempt to move the switch to the normal position can be made.

With apparatus embodying my invention shown in Fig. 2 it is possible to restore the switch to its last operated position immediately and to attempt to operate the movement again in the direction in which it failed.

The main feature of my invention is that since a copper oxide rectifier has the electrical characteristic of lowering its resistance when the voltage across it is increased, the rectifier may be used as a regulating device in the manner described. One advantage resulting from the use of a copper oxide rectifier in the manner described is that, because of the greater resistance change for a given voltage change obtainable with the rectifier as compared with the resistance change of the usual ballast lamp or negative temperature coefficient resistor, a device more sensitive in operation and possessing a greater possible range of adjustment is made available. Another advantage is that since the copper oxide rectifier is practically instantaneous in its response to voltage changes, as contrasted with devices in which a resistance change follows upon a temperature change requiring an appreciable time interval, the speed of operation of the system is increased.

It will, of course, be understood that my invention is not limited to overload protection of a railway switch motor, but may be applied to the control of any load circuit in which it is desired to maintain the load current accurately below a given predetermined value, a slight increase in the load current above the given value being sufficient to cause the breaker to respond. Although a series motor is illustrated, a shunt motor or other suitable type of motor can obviously be protected as well, since the trip winding 23 of breaker R does not have to be connected across the motor field, but may be connected across any suitable impedance in series with the motor. In a series motor, the connection across the field is convenient since no additional impedance is required for obtaining the potential drop used for operating the breaker.

Although I have herein shown and described only one form of apparatus embodying my invention, it is understood that various changes and modifications may be made therein within the scope of the appended claims without departing from the spirit and scope of my invention.

Having thus described my invention, what I claim is:	for energizing said motor, an overload circuit breaker for at times interrupting said circuit, and means for tripping said breaker including a trip winding energized from the potential drop across the field winding of said motor.	80
1. In combination with an electric motor having an armature and a field winding, a circuit for energizing said motor, an overload breaker for at times interrupting said circuit, means for tripping said breaker including a trip winding energized from the potential drop across the field winding of said motor, and a copper oxide rectifier connected in series with said trip winding for causing a relatively large increase in the current through said trip winding with a relatively small increase in said potential drop resulting from an overload on the motor, thereby providing for sensitive overload operation of said breaker.	3. In combination with an electric motor having an armature and a field winding, a circuit for energizing said motor, an overload circuit breaker for at times interrupting said circuit, means for tripping said breaker including a tripping winding energized from the potential drop across the field winding of said motor, and a resistor connected in series with said trip winding and having a relatively high negative resistance voltage characteristic as well as the property of instantaneously varying its resistance in response to changes in voltage.	85
2. In combination with an electric motor having an armature and a field winding, a circuit	BERNARD E. O'HAGAN.	90
